PLAYGROUND ROUNDABOUT

Lee S. Watlington, 1204 N. Linden Ave., Bloomington, Ill.

Filed Dec. 28, 1964, Ser. No. 83,193

Term of patent 7 years

(Cl. D34—5)

FIG. 1 is a perspective view of a playground roundabout showing my new design;

FIG. 2 is a side elevational view thereof, the opposite side being substantially the same;

FIG. 3 is a top plan view thereof.

I claim:

The ornamental design for a playground roundabout, as shown and described.
